UNITED STATES PATENT OFFICE

2,435,711

STROKE CONTROL FOR RECIPROCATING PUMPS

Wilfred Brereton Crofton, Illovo, Johannesburg, Transvaal, Union of South Africa, assignor of one-half to Koppel Engineering (Proprietary) Limited, Johannesburg, Transvaal, Union of South Africa

Application December 27, 1944, Serial No. 569,938
In the Union of South Africa January 28, 1944

6 Claims. (Cl. 103—38)

1

This invention relates to reciprocating pumps, and in particular to windmill driven vertical lift pumps.

Various means have hitherto been proposed whereby the stroke of the pump may be varied at will. In general, however, these means have not served to vary the stroke automatically in accordance with changes in the power of the windmill or other power unit. Alternatively, in cases in which the variation in stroke has been effected automatically, the means for doing so has been complicated in construction, expensive to install, and difficult to maintain in efficient operation.

The object of the present invention is to provide a simple and reliable means for varying the stroke of the pump automatically according to the power available and, to this end, I provide, in accordance with the invention a stroke-varying means which comprises, in combination, a dual transmission arrangement whereby, for a constant stroke of the windmill rod or pitman, the pump rod or plunger can be operated either with the same stroke as the pitman or a stroke different from that of the pitman, and a combined trip and inertia-mass mechanism whereby it is determined, at the end of each idle stroke of the pitman, whether a power stroke will be transmitted to the pump rod or plunger equal to or different from the stroke of the pitman.

Some embodiments of the invention will be described, by way of example, with reference to the accompanying drawings, in which:

Fig. 1 is a front elevation of one form of stroke-varying means embodying the invention, the trip and inertia-mass mechanism being omitted for the sake of clearness.

Figs. 2, 3 and 4 are respectively a front elevation, plan and side elevation, of the said means, illustrating the trip and inertia-mass mechanism.

Figs. 5 and 6 are front elevations of two other forms of stroke-varying means according to the invention, again omitting for clearness the trip and inertia-mass mechanism.

Referring to Figs. 1 to 4 of the drawings:

In the means shown in these figures, the dual transmission arrangement includes a pair of levers 1, 1^a which are connected to pivot pins 2 and 2^a carried by lugs 3, 3^a on the windmill rod or pitman 4. The outer ends of the levers 1, 1^a are fulcrumed on pivot pins 5, 5^a which are carried by links 6, 6^a pivotally connected at 7, 7^a to a bracket 8 which rests on the top of the rising main 9 of the pump.

The pump rod or plunger 10 passes up through

2

the bracket 8 and has a cross-head 11 fixed thereto by nuts 12. The cross-head 11 is fitted with guide rods 13 which are slidable vertically with respect to guide sleeves 14 provided on the windmill rod or pitman 4. Links 15, 15^a connect the cross-head 11 to pivots 16, 16^a situated at or about the middle of the levers 1 and 1^a respectively.

The trip and inertia-mass mechanism comprises a cam or ramp 17 (Fig. 3 and 4) welded firmly to one side of the wind mill rod or pitman 4. A pendulum 18 is mounted on a fulcrum pin 19 mounted in an arm 20 provided on the rising main 9 or other fixed part of the pump. The pendulum 18 has an upwardly-extending arm 21 fitted at the top end with a roller 22. Alternatively, the ramp may be provided on the top of the arm 21, and the roller on the pitman 4. A pusher-bar 23 is connected to the pendulum 18 by a pin 24 just below the fulcrum 19. An apertured bracket 25 is fixed on a lever 26 mounted on a fulcrum 27 carried by an arm 28 secured on the rising main 9. An inner nut 29 and an outer nut 30 are screwed on the end of the pusher bar 23 and a sleeve 25^a is provided on the bar 23 between these nuts to form a replaceable member, whereby the bar will be slidable through the aperture of the bracket 25. An upwardly projecting rod 31 is supported on a compression spring 26^a on the top of the lever 26. On the windmill rod 4, at the side opposite from the ramp 17, a transverse bracket 32 is welded. This bracket carries a fulcrum pin 33. A latch 34 is free to pivot about the pin 33, except as limited in an inward or clockwise direction by a fixed stop 33^a. The windmill rod 4 also has a bifurcated bracket 35 welded thereon, wherein a fulcrum pin 36 is carried, on which is pivoted a vertical or substantially vertical tie-rod 37. A hole 38 is formed in the tie-rod 37 near the bottom thereof. This hole 38 is of a size sufficient to receive a pin or stud 39 which is formed on a cross-piece 40, welded in place between the guide rods 13 (Figs. 2 and 4) of the cross-head 11.

45 The tie-rod 37 is provided with a lateral extension 41 which is under the downward constraint of a compressed spring 42.

The operation of the means just described is as follows:

The balance of the pendulum 18 is such that the roller 22 normally lies in the path of the ramp 17. When the power available to drive the windmill rod or pitman 4 is below a predetermined limit, the ramp will act upon the roller 22 with a force insufficient to cause the pendulum 18 to

displace the pusher-bar 23 any further to the right (Fig. 4) than is indicated by the full-line position of the said bar in Fig. 4, i. e. a distance substantially equivalent to the distance at which the inner and outer nuts 29, 30 are set apart from each other. The movement of the pusher-bar 23 corresponding to the swinging of the pendulum 18 from the innermost position indicated in dotted lines at 18^a to the position shown in full lines in Fig. 4 is thus a lost motion so far as operation of the lever 26 is concerned. Under these conditions of operation, the pump rod 10 remains connected with the windmill rod 4 solely through the cross-head 11, links 15, 15^a and levers 1, 1^a. Since therefore the ratio of the leverages about the fulcrum 5 and 5^a of the pivots 16, 16^a and the pivot pins 2, 2^a is only 1:2, the cross-head 11 and pump rod 10 will move with only one half of the length of stroke of the windmill rod 4 (compare the full line and dotted line positions of the lever arrangement in Fig. 1).

When, on the other hand, the cam or ramp 17 (Fig. 4) strikes or acts against the roller 22 with a force above the predetermined limit, the pendulum 18 will swing aside a sufficient distance to a new position 18^b (shown by chain-dotted lines in Fig. 4) to cause the pusher-bar 23 (through its nut 29) to push the lever 26 in a clockwise direction so that the upwardly-projecting rod 31 is moved aside to the right to a new position 31^a (Fig. 4). After a momentary interval, the latch 34 makes contact with the top of the rod 31, which arrests the downward movement of the latch 34 and causes it to assume the position 34^a shown in dotted lines in Fig. 4. In this position, the nose of the lateral extension 41 of the tie-rod 37 is released from the latch 34 and the compressed spring 42 presses the extension 41 downwards and forces the tie-rod 37 to the left (Fig. 4), so that the pin or stud 39 provided on the cross-piece 40 will engage in the hole 38. This movement or change-over takes place when the windmill rod 4 is temporarily at rest at the bottom of its stroke so that no strain, noise or vibration occurs. When this change-over is complete, the windmill rod 4 and pump rod 10 (along with the bracket 8 and the associated links 6, 6^a, and 15, 15^a and levers 1, 1^a) will move in unison during the ensuing upward or power stroke (see Fig. 2 which illustrates the position of the parts at the completion of this stroke).

The latch 34 is mainly used to prevent wear on the hole 38 and pin 39. At the bottom of the stroke, the cross-head 11 rests on the bracket 8, so that the hole and pin engage and disengage without friction.

At the end of each downward or idle stroke of the windmill rod or pitman 4, the cam or ramp 17 acts upon the pendulum 18 in the manner referred to and determines, according to the amount of swing of the pendulum, whether the next upward or power stroke of the pump rod 10 will be equivalent only to a half of the stroke of the pitman 4, as transmitted through the aforesaid levers 1, 1^a, links 15, 15^a and cross-head 11, or to the whole stroke of the pitman 4, as transmitted through the tie-rod 37. If the power available drops below the predetermined limit, the swing of the pendulum 18 will be insufficient to displace the rod 31, which will thus occupy the position shown in full lines in Fig. 4 when the pitman 4 descends. Consequently, as the pitman approaches the bottom of its stroke, the top of the rod 31 will contact the lateral

extension 41 and force the tie-rod 37 out of engagement with the pin or stud 39. The bevelled nose of the extension 41 will ride upwards past the bottom edge of the notch 43 of the latch 34, which will then move under the nose of the extension 41, and hold the tie-rod 37 in its disengaged position. The direct connection between the windmill rod 4 and pump rod 10 will thus be eliminated, and the windmill rod will continue to drive the pump rod indirectly through the levers 1, 1^a, links 15, 15^a and cross-head 11 until the power again rises above the predetermined limit.

If desired, means may be provided for varying the position of the link or links towards or away from the fulcrum or fulcrums of the aforesaid lever or levers. In this manner, initial adjustments in the fraction of the pitman stroke transmitted by the links to the pump rod can be effected.

Referring to Figs. 5 and 6:

In these figures, alternative forms of dual transmission arrangements are illustrated.

In Fig. 5, instead of the indirect or half-stroke transmission being effected through levers as in the arrangement shown in Fig. 1, it is effected through a double toothed rack 50 fixed to the windmill rod 4, and through twin toothed pinions 51, 52 which are mounted on plates 53 fixed to the pump rod 10 and which are in mesh with twin racks 54, 55. These racks are formed on a rectangular frame 56 through the upper and lower apertures 57 and 58 of which the windmill and pump rods 4 and 10 are slideable. As long as the indirect or half-stroke transmission continues, the frame 56 rests on the top of the rising main 9. Thus, during the working or up strokes, when the double rack 50 rises with the windmill rod 4, the pinions 51, 52 will roll up on the twin racks 54, 55 as a base. As a result, the plates 53 and pump rod 10 travel up only half the distance travelled by the windmill rod 4.

The trip and pendulum mechanism which is used with the transmission arrangement shown in Fig. 5 is identical with that already described with reference to Fig. 4. The pin 39 for engagement with the hole in the tie-rod is formed on the adjacent plate 53 (see Fig. 5). Alternatively, the pin may be provided on the tie-rod and the hole in the plate.

The transmission arrangement shown in Fig. 6 is very similar to that shown in Fig. 5. In lieu of the racks and pinions, two chains 60, 61 and pulleys 62, 63 are provided. The chains are connected to lugs 64, 65 on the rectangular frame 56^a and are led down underneath the pulleys 62, 63 and up to a head 66 fixed on the lower end of the windmill rod 4. During the half-stroke transmission, the chains 60, 61, on each working or up stroke, will raise the pulleys 62, 63 only one-half stroke. These pulleys are mounted in plates 67 fixed to the top of the pump rod 10 which thus receives, under these conditions, only strokes equal to one-half of the strokes of the windmill rod 4. The reference numeral 68 indicates the hole (or pin) adapted to be engaged by the pin (or hole) of the tie-rod 37 (Fig. 4) for direct or full stroke operation.

As will be apparent, although, in the constructions described, provision is made for transmission to the pump rod of only either the full stroke of the pitman or one particular fraction of such stroke, the range of the overall variation of the power ratio is very wide since the incidence and number of fractional strokes which are interposed in series with full power strokes will vary

automatically according to the power available at the windmill rod or pitman, from time to time. Thus, each full stroke of the pump rod may be followed by a fractional stroke of the same, or every two consecutive full strokes may be followed by one fractional stroke, and so on.

Various modifications may be made in the means described without departing from the scope of the invention. For example, instead of employing a pendulum as an inertia-mass, I may employ an inertia wheel.

I claim:

1. Means for varying the stroke of reciprocating pumps comprising, in combination with a driving rod and a pump rod, transmission means connected to the driving rod and the pump rod for driving the latter, and inertia means connected to the pump rod and operable by the driving rod in dependence upon the speed and power of the latter to vary or adjust the movement of the pump rod according to the force exerted by said driving rod.

2. Means for varying the stroke of reciprocating pumps comprising, in combination with a driving rod and pump rod, means for directly connecting said driving rod to said pump rod, transmission means adapted to transmit power from said driving rod to said pump rod with a mechanical advantage, and inertia mechanism connected to the pump rod operable at the end of each idle stroke of said driving rod to adjust the stroke of the pump rod upon a change in the power of the driving rod.

3. Means for varying the stroke of reciprocating pumps comprising, in combination with a driving rod and pump rod, means for connecting said driving rod directly to said pump rod, transmission means adapted to transmit power from said driving rod to said pump rod with a mechanical advantage, an inertia responsive device connected to the pump rod and operable by the driving rod including means whereby said device is set in motion at each idle stroke by said driving-rod, and trip mechanism connected to the driving rod to uncouple the connecting means and to couple together said driving rod and pump rod through said transmission means when said

inertia-mass device is acted on with a predetermined force by said driving rod.

4. Stroke-varying means according to claim 1, in which the transmission means comprises a tie-rod to act as a direct connection between said driving rod and pump rod, and a device is provided as a mechanical advantage in the transmission between said rods.

5. Stroke-varying means according to claim 2, in which said transmission means comprises a lever device.

6. Means for varying the stroke of reciprocating pumps comprising, in combination with a driving rod and pump rod, means for directly connecting said driving rod to said pump rod, transmission means adapted to transmit power from said driving rod to said pump rod with a mechanical advantage, and inertia mechanism connected to the pump rod operable at the end of each idle stroke of said driving rod to adjust the stroke of the pump rod upon a change in the power of the driving rod, said inertia mechanism comprising a cam connected to said driving rod, a tie-rod pivotally secured to said driving rod, an element on said pump rod engageable by said tie-rod, spring means adapted normally to maintain said tie-rod in engagement with said element, and a pendulum projecting into the path of said cam to be acted on by said cam with a predetermined force near the bottom of the stroke to detach said tie-rod from said element and establish a connection between said driving rod and pump rod through said transmission means.

35 WILFRED BRERETON CROFTON.
